UNITED STATES PATENT OFFICE.

LEWIS E. WEGNER, OF HOT SPRINGS, ARKANSAS.

WRENCH.

1,277,162.

Specification of Letters Patent. Patented Aug. 27, 1918.

Application filed October 19, 1917. Serial No. 197,381.

To all whom it may concern:

Be it known that I, LEWIS E. WEGNER, a citizen of the United States, residing in Hot Springs, Garland county, State of Arkansas, have invented Wrenches, of which the following is a specification.

One object of my invention is to provide a relatively simple, substantial and practical form of sliding jaw wrench which may be quickly adjusted to suit it to operate upon objects of widely varying sizes and which shall be none the less positive in action and not likely to get out of order.

I further desire to provide a wrench of the type noted with novel means for moving and thereafter holding its sliding jaw in any desired position; the invention contemplating a novel construction of operating handle and holding means designed to coöperate with the sliding element.

It is further desired to provide a wrench of the type noted with a movable jaw of novel form and method of action, together with a novel form of operating handle and stirrup associated with said jaw.

These objects and other advantageous ends I secure as hereinafter set forth, reference being had to the accompanying drawings, in which,

Figure 1 is a side elevation of a wrench constructed in accordance with my invention;

Figs. 2 and 3 are elevations partly in section, showing the slidable jaw and its associated parts in the positions occupied when said parts are free to be adjusted and when they are locked, respectively;

Figs. 4 and 5 are transverse sections on the lines 4—4 and 5—5, respectively, Fig. 1;

Figs. 6 to 9 inclusive are perspective views of certain of the principal parts of the wrench;

Figs. 10 and 11 are perspective views of the two supplementary jaws with their pivot pins which may be employed in connection with the main jaws of the wrench;

Figs. 12 and 13 are perspective views of the holding pawl and of the toothed adjusting wheel respectively;

Fig. 14 is a perspective view of the main pivot pin;

Fig. 15 is a side elevation, partly in sec-

tion illustrating a modification of my invention; and

Fig. 16 is a perspective view of a special form of auxiliary jaw.

In the above drawings, 1 represents the shank or body of the wrench which at one end has a portion 2 projecting to one side and constituting a fixed jaw. The main portion of the shank is preferably of rectangular section and on that side from which the jaw 2 projects, is provided with a series of teeth 3 which are preferably made with sides projecting parallel to the jaw and inclined or V-shaped ends.

On this shank or body of the wrench is mounted a sliding or adjustable jaw 4 which has an opening for the reception of said shank of greater length than the transverse breadth of the shank and includes a rearwardly projecting arm 5 which at its rear end is perforated for the passage of a transverse pivot pin or screw 6 for the attachment of a stirrup 7 and the forks or arms 75 of an operating handle 8. Said stirrup is of U-shaped section so as to extend around the shank 1 and has fixed to it adjacent the back face of said shank a convex spring plate 7^a whose ends are bent as shown in 80 order to permanently retain it on said stirrup. It is noted that the hole for the pivot pin 6 extends through the sides of the stirrup to one side of the center line thereof, and said sides fit snugly against the sides 85 of the handle so as to in some degree assist the spring 11 to hold the pawl 9 in engagement with the teeth 3 when the jaws grip an object and also to frictionally resist the automatic release of the wrench.

While the main or outer portion of the handle 8 is preferably of U-shaped section, its inner end has the form of two parallel plates, between which, on the upper side of the pivot pin 6, is pivoted or journaled a 95 holding pawl 9. This latter has the general shape of a triangular prism and on one face has a series of teeth, preferably of the same shape or section as and designed to coat with, the teeth 3 of the shank 1. This pawl 100 is so mounted on the handle 8 that when the latter is swung on its pivot 6 into the position shown in Figs. 1 and 2 wherein it projects at a relatively large angle to the shank

of the wrench, the toothed face of said pawl is separated from and completely clears the toothed portion of the shank. The distance said handle may be swung out from the shank and therefore the distance that the pawl 9 may be moved away from the teeth 3 is limited by a toothed wheel 10, pivoted between the side plates of the handle 8 on the opposite side of the pin 6 from the pawl 9;—the arrangement being such that said wheel, which coöperates with said shank, comes into engagement with the latter when the handle 8 has been turned to swing the pawl its maximum distance away from the teeth 3.

Within the handle 8 and extending longitudinally thereof I provide a flat spring 11 which at one end is riveted or otherwise suitably fixed to it, while its opposite end, 20 which engages the rear or untoothed face of the shank 1 so as to return the handle 8 to its open or spread position, has fixed to its free extremity a T-shaped piece 12. This latter has arms which are so positioned as 25 to bear respectively upon the side plates of said handle after the free end of the spring has moved inwardly a predetermined distance;—the arrangement being such that the piece 12 holds the free end of said spring 11 out of engagement with the rear face of the shank, after the handle has been opened or spread away from said shank to its maximum extent in order to permit movement of the jaw 4.

While the coacting faces of the fixed and movable jaws 2 and 4 for certain purposes may be plane or flat, I preferably mount on them a pair of auxiliary jaws 13 and 14 preferably of identical form and hold them in place by pins 15 and 16. One form of such auxiliary jaws has toothed faces (Figs. 10 and 11), or it may have gripping teeth of stepped form for gripping a pipe as shown at 30 in Fig. 15, or in some cases the jaws 45 may be formed to serve as a vise as indicated at 31 in Fig. 16.

It is to be noted that the shank 1 of the wrench loosely fits the opening 19 of the movable jaw 4 so that the latter may have a limited swing on its pivot 6 in order that its work-engaging face shall engage and properly conform to the shape of an object to be gripped. For this purpose said opening is abruptly contracted at its forward end 55 to form fulcrum edges 32 and 33 and flares rearwardly from these latter as shown in Figs. 2 to 4 inclusive.

In order to adjust the sliding jaw on the shank 1, the handle 8 is brought to the position shown in Figs. 1 and 2 and said jaw is moved parallel to the line of the shank 1, either by force applied directly to it or by the operator turning the toothed wheel 10 by a finger or thumb. When the movable 65 jaw has been brought to the desired posi-

tion which will permit an object to be loosely gripped between the jaws, the handle 8 is forced toward the shank 1, with the result that the toothed face of the pawl 9 is first brought into engagement with the teeth 3 70 after which the pivot pin 6 acts upon the projecting arm 5 of the jaw to swing it on its fulcrum edge 32 and move its work-engaging face farther toward the fixed jaw.

If for any reason it be desired to maintain the jaws in their work-engaging positions, I provide a link 20 detachably or otherwise mounted in a slot or hole 21 in the lower or outer end of the shank and turn it so that it fits over the free end of the handle 8 thereby holding the parts in the positions shown in Fig. 3. It is to be noted however that with the construction of spring 11 illustrated, the pawl remains in engagement with the teeth 3 even after the handle 80 has been released, so that while the movable jaw releases the object previously gripped, the general adjustment of said jaw is not affected. To accomplish such adjustment the handle is turned to its extreme outer position so that its relation to the stirrup 7 is altered and the pawl lifted bodily away from the teeth 3. There is therefore no friction on or interference with the free movement of the slidable jaw on the shank 1 as long as 90 the handle is maintained in its outer or open position, since the cross arms of the piece 12 are then supported by the side plates of the latter and hold said spring away from the adjacent surface of the shank.

In certain cases, especially when the wrench is of comparatively large size, I may provide a spring tooth 22 on the rear or lower end of the arm 5 of the slidable jaw and hold it in place by a spring washer 24 105 and a pivot screw or bolt 23. This tooth is so formed that it is rotatably on said bolt to the rear of the toothed wheel 10 and when the handle 8 is in its open or outer position it may be turned to said bolt into or out of engagement with the teeth 3 of the shank. When so engaged the movement of the handle toward the shank first moves the pawl 9 into engagement with the teeth 3 and then as the movable jaw 4 is swung toward the 115 fixed jaw 2, causes the spring tooth 22 to drag over one of said teeth into engagement with the next tooth in front of the same. Thereafter the swinging out of the handle frees the pawl 9 from the teeth 3 and its 120 subsequent moving toward the shank causes said pawl to again engage said teeth one tooth in advance of its original position. It is thus possible to gradually and intermittently move the jaw 4 toward the jaw 2 125 merely by oscillating the handle 8.

I claim:

1. The combination in a wrench of a toothed shank having a relatively fixed jaw; a movable jaw slidable on the shank and 130

having a projecting arm; a stirrup extending around the shank; an operating handle; a pivot connecting the arm, the stirrup and the handle; and a pawl on the handle in position to engage the teeth of the shank when said handle is operated.

2. The combination in a wrench of a toothed shank having a relatively fixed jaw; a movable jaw slidable on the shank and 10 having a projecting arm, said latter jaw having an opening with a fulcrum edge therein for the shank; a stirrup extending around the shank; an operating handle; a pivot connecting the arm, the stirrup and 15 the handle; and a pawl on the handle in position to engage the teeth of the shank when said handle is operated.

3. The combination in a wrench of a toothed shank having a relatively fixed jaw; 20 a movable jaw slidable on the shank and having a projecting arm; a stirrup extending around the shank; an operating handle having branches frictionally engaged by the sides of the stirrup; a pivot connecting the 25 arm, the stirrup and the handle; and a pawl on the handle in position to engage the teeth of the shank when said handle is operated.

4. The combination in a wrench of a toothed shank having a relatively fixed jaw; 30 a movable jaw slidable on said shank and having a projecting arm; a stirrup extending around the shank; an operating handle; a pivot connecting the arm, the stirrup and the handle; a pawl mounted on the handle 35 in position to engage the teeth of the shank when said handle is operated; and a toothed wheel mounted to coöperate with the teeth of the shank to move the slidable jaw and handle thereon.

40 5. The combination in a wrench of a toothed shank having a relatively fixed jaw; a movable jaw slidable on the shank and having a projecting arm; a stirrup extending around the shank; an operating handle; a pivot connecting the arm, the stirrup and the handle; a pawl mounted on the handle 45 in position to engage the teeth of the shank when said handle is operated; and a toothed wheel also coöoperating with

50 the teeth of the shank for moving the slidable jaw and handle thereon, the toothed pawl being on one side of the pivot and the toothed wheel on the opposite side thereof.

6. The combination in a wrench of a 55 toothed shank having a relatively fixed jaw; a movable jaw slidable on said shank; a stirrup for the movable jaw; a handle pivotally connected to the movable jaw; and a pawl and a toothed wheel mounted on the handle, 60 said pawl being positioned to engage the teeth of the shank when the wheel is disengaged therefrom and vice versa.

7. The combination in a wrench of a shank having teeth on one face and a fixed 65 jaw projecting from said face; a movable

jaw slidable on the shank; a forked handle projecting from the side of the shank opposite that having the teeth; a pivot connecting the forks of the handle to the movable jaw adjacent the teeth of the shank; a 70 stirrup connected to the handle by said pivot; and a pawl mounted on the handle in position to engage the teeth of the shank when said handle is moved.

8. The combination in a wrench of a 75 toothed shank having a fixed jaw on the same side as its teeth; a movable jaw slidable on and including a work-engaging portion projecting at one side of said shank; a handle having portions extending on opposite sides of the shank and pivoted to said movable jaw; a pawl carried by the handle on the same side of the shank as said jaws and positioned to coöperate with the teeth of said shank; and a spring on the handle 85 normally maintaining it in position inclined to the line of the shank.

9. The combination in a wrench of a toothed shank having a fixed jaw; a movable jaw slidable on said shank; a handle 90 having portions extending on opposite sides of the shank and pivoted to said movable jaw; a pawl on the handle in position to coöperate with the teeth of the shank; a spring carried by the handle and operative on the 95 shank to move said handle with the pawl to a shank disengaging position; and means for preventing operation of the spring on the shank when the handle is in the jaw-releasing position.

10. The combination in a wrench of a toothed shank having a relatively fixed jaw; a movable jaw slidable on said shank and having a projecting arm; a forked handle pivoted to said arm; a pawl carried by said 105 handle in position to coöperate with the teeth of the shank; a flat spring on the handle projecting toward the shank; with a member connected to the spring and operative on the handle to hold said spring out of engagement with the shank when the handle is in the jaw-releasing position, said member consisting of a cross piece engaging the branches of the handle to limit movement of said spring toward the shank.

11. The combination in a wrench of a toothed shank having a fixed jaw; a jaw movable on said shank and having a projecting arm; a stirrup and a handle concentrically pivoted to said arm; a pawl 120 mounted on the handle in position to coöperate with the teeth of the shank; a spring on the handle in position to resist movement thereof in one direction relative to the shank; and a headed member operative on the handle to hold said spring out of engagement with the shank when said handle is in its jaw releasing position.

12. The combination in a wrench of a toothed shank having a fixed jaw; a mov- 130

- able jaw slidable on the shank and having a projecting arm; a handle pivoted to the arm; a pawl pivoted to said handle; and a stirrup extending around the shank and also pivoted to the handle.
13. The combination in a wrench of a toothed shank having a fixed jaw; a movable jaw slidable on the shank; a handle pivoted to said latter jaw; a stirrup also pivoted to the handle and extending around the shank; a pawl carried by the handle in position to engage the teeth of the shank; and a spring between the stirrup and the shank.
14. The combination in a wrench of a shank having a relatively fixed jaw and provided with teeth; a movable jaw slidable on said shank; a handle pivoted to said movable jaw; a pawl carried by the handle in position to coöperate with the teeth of the shank; and a toothed member mounted on the movable jaw in position to also coöperate with the teeth of the shank.
15. The combination in a wrench of a toothed shank having a fixed jaw; a movable jaw slidable on said shank and having a projecting arm; a tooth mounted on said arm in position to coöperate with the teeth of the shank; a handle pivoted to said arm; and a pawl on said handle in position to also coöperate with the teeth of the shank.
16. The combination in a wrench of a toothed shank having a fixed jaw; a slidæble jaw on the shank; a handle; a pivot connecting said handle to the slidæble jaw; and two toothed members mounted on the handle eccentrically to the pivot in position for either of them but not both to engage the teeth of the shank when said handle is moved through an angle of less than 90°.
17. The combination in a wrench of a shank; fixed and movable jaws on said shank; a handle pivoted to the movable jaw; a pawl carried by the handle in position to engage the shank when said handle is in one position; and means carried by the movable jaw for holding it from movement when said pawl is released from the shank.
18. The combination in a wrench of a shank; fixed and movable jaws on said shank; a handle pivoted to the movable jaw; a pawl carried by the handle in position to engage the shank when said handle is in one position; and a second pawl carried by the movable jaw for preventing it from moving when the first pawl is released from the shank.
19. The combination in a wrench of a shank; a fixed jaw thereon; a member movable on the shank and including a second jaw; a handle movably connected to said member and operative to hold to the shank when in one position; and means for preventing movement of said jaw-carrying member when the handle is in another position.
20. The combination in a wrench of a toothed shank; a fixed jaw thereon; a member slidæble on the shank and including a second jaw; a tooth carried by said member in position to coöperate with the teeth of the shank; a handle pivoted to the member; and a pawl carried by the handle and also coöoperative with the teeth of the shank.
21. The combination in a wrench of a toothed shank; a fixed jaw thereon; a member slidæble on the shank and including a second jaw; a tooth carried by said member in position to coöperate with the teeth of the shank; a handle pivoted to the member; and a pawl carried by the handle and also coöoperative with the teeth of the shank, said tooth being adjustable relatively to the jaw-carrying member into and out of a shank-engaging position.
22. The combination in a wrench of a toothed shank; a fixed jaw thereon; a member slidæble on the shank and including a second jaw; a spring tooth carried by said member in position to coöperate with the teeth of the shank; a handle pivoted to the member; and a pawl carried by the handle and also coöoperative with the teeth of the shank.

In witness whereof I affix my signature. 95
LEWIS E. WEGNER.
